(57) CLAIM

The ornamental design for a recessed, flush mounted housing for a smoke, carbon monoxide or temperature detector and alarm, as shown and described.

DESCRIPTION

FIG. 1 is a perspective view of the recessed, flush mounted housing for a smoke, carbon monoxide or temperature detector and alarm of my invention shown installed in a wall, partition or ceiling which is depicted in broken lines: FIG. 2 is a front view of the recessed, flush mounted housing for a smoke, carbon monoxide or temperature detector and alarm of my invention shown installed in a wall, partition or ceiling which is depicted in broken lines;

FIG. 3 is a cross sectional view taken along line 3—3 of FIG. 2 to clarify the contour or configuration of the external surface of the claimed design with the internal construction shown in broken lines and not forming a part of my claimed design;

FIG. 4 is a cross sectional drawing taken along lines 4—4 of FIG. 2 to clarify the contour of the exterior surface of the claimed design with the internal construction shown in broken lines and not forming a part of my claimed design; FIG. 5 is a right side elevational view of FIG. 2 with the left side being a mirror image thereof with the internal structure shown in broken lines and not forming a part of my claimed invention; and,

FIG. 6 is a bottom end view of the recessed, flush mounted housing for a smoke, carbon monoxide or temperature detector and alarm as shown in FIG. 2 with the top end view being a mirror image thereof with the internal structure shown in broken lines and not forming a part of my claimed invention.

The broken lines shown in the drawings are to illustrate the environment such as the wall, partition or ceiling and apertures of FIGS. 1 and 2, the internal construction shown in FIGS. 3, 4, 5 and 6 and the alarm test light and button shown in FIGS. 5 and 6 and form no part of my claimed design. The back view cover of the plate is the reverse of the front view and is devoid of surface ornamentation. The broken line showings of FIGS. 1, 2, 3, 4, 5 and 6 of the drawings are for illustrative purposes only and form no part of the claimed design.
